United States Patent Office

Des. 178,744

Patented Sept. 11, 1956

178,744

JACKET

Louis Warmflash, Elizabeth, N. J., assignor to Blue Bell, Inc., Greensboro, N. C., a corporation of North Carolina

Application May 26, 1955, Serial No. 36,243

Term of patent 14 years

(Cl. D3—4)

Fig. 1.

Fig. 2.

Fig. 1 is a front view of a jacket, showing my new design.

Fig. 2 is an enlarged sectional detail on line 2—2 of Fig. 1.

The back is plain and unornamented.

I claim:

The ornamental design for a jacket, as shown and described.
